UNITED STATES PATENT OFFICE.

ALEXANDER N. SCOTT, OF CANTON, OHIO, ASSIGNOR TO THE DIEBOLD SAFE & LOCK COMPANY, OF CANTON, OHIO, A CORPORATION OF OHIO.

AUXILIARY LOCK.

Application filed January 31, 1922. Serial No. 532,938.

To all whom it may concern:

Be it known that I, ALEXANDER N. SCOTT, a citizen of the United States, residing at Canton, in the county of Stark and State 5 of Ohio, have invented certain new and useful Improvements in Auxiliary Locks, of which the following is a specification.

The invention relates to an auxiliary or a secondary lock for the doors of safes, vaults 10 and the like, designed to supplement or take the place of the ordinary lock when the same is maliciously or otherwise opened by means involving a heating of the door; and the object of the improvement is to provide a suspended and normally inoperative bolt which will be released for locking the door when the same is heated to more than a normal temperature.

The object of the invention is attained 20 by suspending a heavy bolt in an upright channel provided therefor in the body of the door or in a guide way on the inner side of the door, by means of a chain including in its length a series of spaced links made of 25 fusible metal or alloy which will melt at a temperature slightly above that to which the door is ordinarily exposed.

Restraining means for an auxiliary bolt which must be cut or severed by the direct 30 action of a tool or flame, can only release the bolt when the restraining means happen to be in the path of the tool or the flame; while the suspending means of the present improvement is located in or near along the 35 body of the door and will be severed by indirect heat caused by a flame or other source at a comparatively low temperature but little above the normal temperature of the door.

40 The invention may be embodied in or on the door of a safe in the manner shown in the accompanying drawings, forming part hereof, in which—

Figure 1 is an elevation of the inner side 45 of a safe door, with parts broken away to show the auxiliary lock suspended in the body of the door;

Fig. 2, vertical section of the same on line 50 II—II, Fig. 1;

Fig. 3, an enlarged fragmentary section on line III—III, Figs. 1 and 2;

Fig. 4, a detached perspective view of an ordinary link of the suspending chain or cable;

Fig. 5, a detached perspective view of a 55 fusible link;

Fig. 6, an elevation of the inner side of a safe door, with portions of the ordinary mechanism broken away to show the auxiliary lock suspended between the same and the back of the door; and

Fig. 7, a vertical section of the same on line VII—VII, Fig. 6.

Similar numerals refer to similar parts 65 throughout the drawings.

In a preferred form of the improvement, the auxiliary lock comprises an elongated bolt of considerable weight suspended in a vertical way 9 provided in the body of the door, by means of a chain including series of 70 ordinary links 10 and fusible links 11 alternating with each other and supported above by a screw stem 12, by means of which the normal height or position of the bolt may be adjusted.

When a safe door is made up of a series of metal plates and laminations, the way 9 for the auxiliary bolt and its suspending chain may be made by forming corresponding 80 channels 9' and 9'' in the contiguous faces of the abutting plates 13 and 13', as shown in Fig. 3; and the size and section of the way is such that the bolt is free to rise and fall without binding therein.

When this form of construction is employed, the way 9 is continued by suitable bores or channels 14 and 14' through the upper and lower frame members 15 and 15' of the door 16, and the bore in the upper member may be tapped with a thread for the screw stem 12, and the same may be adjusted so that the lower end 17 of the bolt 8 is positioned slightly but clear above the bottom of the door.

A socket 18 is provided in the sill 19 of the door for receiving the bolt, which socket is aligned with the bolt way when the door is closed, so that the lower end of the bolt will drop by its own weight into the socket when the suspending chain is severed, as by the melting of one of the fusible links.

The fusible links 11 are made of any well known metal or alloy which will melt at a comparatively low temperature, as for instance, 165° F., so that whenever any portion of the door through which the chain passes is heated to such a temperature, the same will be severed by a melting of one of

the fusible links and the bolt will automatically drop into operative position.

A single auxiliary bolt may be suspended in a way located in the median line of the door, thereby passing in front of or adjacent to the ordinary locking device 29 and 29' and the timing device 20 by which the ordinary locking system is actuated and controlled, so that any effort which may be made to cut through the door by an oxy-acetylene torch or the like, will necessarily heat the adjacent portions of the body of the door to such a degree that one or more of the fusible links will be melted and the auxiliary bolt released to lock and secure the door, even though the ordinary locking system may be opened.

In the modified arrangement shown in Figs. 6 and 7, the auxiliary bolt 8' is located in guides 15" mounted on the back of the door 16' and the chain comprising the ordinary links 10' and the fusible links 11 may be suspended in a retracted or inoperated position from a suitable support 12' secured to the back of the door, and extend along and near the body thereof.

The proximity to the back of the door of the fusible link chain by which the bolt is suspended, will cause the links to be affected by any abnormal or extraordinary heat to which the door or any adjacent portion of it

may be subjected, with the result that the fusible links will be melted and the auxiliary bolt dropped into locking position, the same as described for the preferred arrangement of the same.

Ordinarily a single auxiliary bolt suspended in the median line of the door will be sufficient for all practical purposes, but a plurality of auxiliary bolts may be located at spaced intervals apart so as to cover substantially the entire width of the door, and protect any vulnerable portions thereof which may be exposed to malicious attack.

35

40

45

I claim:—

1. An auxiliary lock for safe doors or the like including a vertical guide-way therein, a bolt-weight in the guide-way, and a chain connected above to the door and extending downward along the body thereof to be directly heated thereby and having a plurality of fusible links therein normally suspending the bolt in retracted position.

50

2. An auxiliary lock for safe doors or the like including a vertical guide-way within the body thereof to be directly heated thereby, a bolt-weight in the guide-way and a chain in the guide-way connected above the door and having a plurality of fusible links therein normally suspending the bolt in retracted position.
